United States Patent Office

Des. 207,338
Patented Apr. 4, 1967

207,338

LAMP

Kazuma Nakao, Inuyama, Japan, assignor to Whitehall
Overseas Corporation, New York, N.Y.

Filed May 27, 1966, Ser. No. 2,455

Claims priority, application Japan Jan. 12, 1966

Term of patent 14 years

(Cl. D48—20)

FIG. 1

FIG. 1 is a front perspective view of a lamp, showing my new design in which the cover is shown in the closed position.

FIG. 2 is a further front perspective view thereof in which the cover is shown in open position.

FIG. 3 is a rear plan view thereof in which the cover is shown in open extended position.

FIG. 4 is a front plan view thereof showing the cover in open extended position.

FIG. 5 is a side perspective view thereof showing the cover in open extended position.

I claim:

The ornamental design for a lamp, as shown and described.
